(57) **CLAIM**

The ornamental design for a computing device display screen with graphical user interface for internet-based spill risk data input, as shown and described.

DESCRIPTION

The FIGURE is a front view of a computing device display screen with graphical user interface for internet-based spill risk data input, showing the claimed design.

The outermost broken line rectangle shows a display screen and forms no part of the claimed design. All other broken lines show portions of the graphical user interface and form no part of the claimed design.

1 Claim, 1 Drawing Sheet

What type of area is this?
 Industrial Residential Institutional Commercial Residential

What is the volume of the largest liquid storage container in this area? (In gallons)

What are the primary types of liquids stored or used in this area? (Select all that apply)
 Industrial Residential Commercial

Is there a drain, with 25% of liquid content?
 Yes No

Do you have a drain blocking or drain sealing device placed in this area?
 Yes No

What does the spill kit in this area look like?
 Spill kit in a cabinet Spill kit in a box Spill kit in a bag Spill kit in a case Spill kit in a drum

Do you use secondary containment (such as containment pallets or isolated berms) in this area?
 Yes No

Do you give employees annual spill response training?
 Yes No

What type of area is this? ▾

Unlined storage Purifying Hazardous waste storage
 Bulk storage Bulk storage/processing Waste accumulation
 Flammable storage Safety cabinet Other

What is the volume of the largest liquid storage container in this area? (In gallons)* ▾
Please enter a value between 1 and 5000

Which are the primary types of liquids stored or used in this area? (Select all that apply) ▾

Water-based liquids Oil-based liquids
 Fuels/flammables Corrosives (acids/bases)
 Oils/greases

Is there a drain within 300ft of liquid containers? ▾

Yes No

Do you have a drain blocking or drain sealing device stored in this area? ▾

Yes No

What does the spill kit in this area look like? ▾

Make your choice based on size, not content.

Do you use secondary containment (such as containment pallets or installed berms) in this area? ▾

Not at all Secondary
 As required by code More than required
 Everywhere

Do you give employees annual spill response training? ▾

Yes No
